PRODUCTION OF MOTOR FUEL

Edward H. Lang, Chicago, Ill., assignor to The Pure Oil Company, Chicago, Ill., a corporation of Ohio

Application June 4, 1941, Serial No. 396,495

2 Claims. (Cl. 196—12)

1

This invention relates to production of motor fuel.

Various methods are known for converting hydrocarbon oils and gases into motor fuel. The methods which are in common usage are thermal cracking of oils at high temperatures and thermal or catalytic polymerization of hydrocarbon gases. Reforming of low octane naphtha either with or without catalyst is also commonly practiced. In all these methods the resulting product is highly unsaturated or olefinic.

Experience has shown that highly olefinic motor fuels have certain disadvantages. First, their susceptibility to lead is low as compared with paraffinic hydrocarbons. Moreover, under high speed operating conditions olefinic hydrocarbons have a tendency to cause knocking in modern automotive engines of high compression ratio.

The object of this invention is to provide a method for producing a well-balanced motor fuel which performs without knocking at all speeds.

Another object of this invention is to provide a method for treating a mixture of hydrocarbons boiling within the gasoline range and containing a high percentage of olefinic hydrocarbons, to produce a well-balanced motor fuel.

Still another object of this invention is to provide a method for converting hydrocarbon oil into motor fuel which gives a high road performance test.

A further object of the invention is to convert hydrocarbon gases into motor fuel which gives a high road performance test.

Still a further object of the invention is to provide a method for improving performance of motor fuels by proper treatment of particular fractions and reblending of the fractions after treatment.

Other objects of the invention will become apparent from the following description and the accompanying drawing of which the single figure is a diagrammatic elevational view of apparatus suitable for carrying out the invention.

Referring to the drawing, numeral 1 indicates a line through which fresh oil is fed to the unit. The fresh oil may be gas oil, kerosine or naphtha or it may be residuum where it is desired to practice vis-breaking. The fresh oil is fed into the upper portion of the absorber 3 where it passes in countercurrent contact with hydrocarbon gas which enters the bottom of the absorber through the line 5. The absorber is maintained under suitable pressure which may vary from 100 to 400 pounds per square inch and the temperature is maintained in the absorber at approximately

5 70-90° F. In the absorber substantially all the C₃ and heavier hydrocarbons are absorbed from the gas together with minor amounts of lower boiling gases. The unabsorbed gas consisting primarily of C₁ and C₂ hydrocarbons together with a small amount of hydrogen and higher boiling hydrocarbons, leaves the top of the absorber through the line 7 controlled by valve 9.

The fat oil, i. e., charging stock containing dissolved therein hydrocarbon gases, leaves the bottom of the absorber through line 11, passes through heat exchanger 13 and is then pumped by means of pump 14 through heating and reaction coil 15. The fat oil may be heated in its 10 passage through coil 15 to a temperature of from 900° to 1150° F., depending upon the nature of the oil. Where residuum stock is being treated, the temperature will be in the neighborhood of 900° F. Where the process is used for conversion of 15 naphtha, temperatures approaching 1150° F. may be used and where stocks boiling intermediate between residuum and naphtha are processed, temperatures will be intermediate between 900° and 1150° F.

20 25 The fat oil is forced through coil 15 at a pressure which may vary from approximately 500 to 3000 pounds per square inch and the time of residence in the coil 15 is sufficient to obtain the desired amount of conversion. The nature of the 20 reaction in the coil 15 is rather complex. Cracking of the oil and gas takes place concurrently with alkylation and polymerization. Because of the high temperatures to which the products are subjected in the coil 15, the resultant products 30 are highly unsaturated. The olefinic content of the reaction products may be 35 to 50% or more.

The reaction products leave the coil 15 through 35 valve 17 where the pressure may be reduced to 500 pounds per square inch or less, pass through heat exchanger 13 where the temperature is reduced to approximately 350° to 550° F. by indirect heat interchange with the charge to the coil 15 and then pass into the lower portion of the fractionating tower 19. The temperature to which 40 45 the reaction products are reduced prior to entering the fractionating tower will depend largely on the nature of the charging oil. With heavier charging stocks the temperature of cooling should be close to 550° F. in order to avoid partial condensation in the heat exchanger with resultant coke deposition. With lighter charging stocks the dew point of the reaction products is considerably lower and therefore lower cooling temperatures may be used.

50 55 In the fractionating tower separation of the re-

action products into residuum, recycle stock, heavy gasoline distillate, light gasoline distillate and gas takes place. The residuum is withdrawn through line 21 controlled by valve 23 and it may be discharged from the system and used as fuel oil. The recycle stock which is heavier than the gasoline distillate is withdrawn from the tower through line 24 and may be recycled to the absorber through valve 25, line 26, cooling coil 27 and line 29, or may be withdrawn from the system through line 31 controlled by valve 33, or may be charged by means of line 35 and pump 36 either to the reaction coil 15 or through cooling coil 37 and line 38 to line 39 to act as quenching liquid for the reaction products, where temperatures lower than those resulting from the exchanger 13 are desired. It will be apparent that the recycle stock may be divided in any desired manner. Uncondensed gas is withdrawn from the top of the fractionating tower through line 40 controlled by valve 41, and cooling coil 42, and charged to absorber 3.

The heavy gasoline distillate is withdrawn from the fractionating tower through line 43 controlled by valve 44. This distillate may have an initial boiling point of between 200° to 250° F. and an end boiling point of approximately 400° F. The boiling range of this fraction may vary somewhat, but in any event it should be within the upper gasoline boiling range. The distillate passes to the reactor or reaction chamber 45 containing anhydrous aluminum chloride preferably deposited on a solid comminuted material such as silica or fuller's earth. If the distillate is not sufficiently warm as it enters the reaction chamber 45, the reaction chamber may be heated to bring the temperature up to approximately 100°-250° F. Ordinarily, the distillate will be sufficiently warm as it leaves the fractionating tower so as not to require additional heating. As the heavy gasoline distillate enters the aluminum chloride reaction chamber it is mixed with methyl and/or ethyl chloride which enter the gasoline stream through line 46. In the presence of aluminum chloride these chlorides react with the gasoline in such manner as to alkylate the unsaturated hydrocarbons contained therein to form saturated iso-paraffins. The reaction products leave the reaction chamber 45 through line 47, pass into separator 48 where the liquid hydrocarbons are separated from the gases which may consist of hydrogen chloride, chlorine and unconverted hydrogen and hydrocarbon gases. The liquid hydrocarbons are mixed with the light gasoline distillate which is withdrawn from fractionating tower 19 through line 49 controlled by valve 51 and the blend is passed through line 53 into fractionator 55 where it is subjected to heating and fractionation to separate end point gasoline. The gasoline vapors pass overhead, are withdrawn through line 57, condensed in cooling coil 59 and collected in receiver 61. The heavy ends are withdrawn from the fractionating tower through line 63 controlled by valve 65 and may be recycled for further conversion. The gasoline distillate may be given a caustic wash or other suitable treatment if necessary to remove any traces of chlorine or hydrochloric acid which remain therein.

The alkylation reaction in the reactor 45 may take place at atmospheric or superatmospheric pressure but it is preferably carried out at pressures of the order of 100 to 350 pounds per square inch. Higher pressures may be used if desired.

The gases from separator 48 leave the top there-

of through the line 67 and are mixed with air which enters the line 67 through line 69. The mixture then passes into the chlorine regenerator 71 which may contain a saturated cuprous chloride solution on pumice. In the presence of the cuprous chloride the air oxidizes the hydrochloric acid, liberating chlorine. The chlorine regenerator should be heated to a temperature below 750° F. but sufficiently high to cause the reaction to take place. The reaction products leave the regenerator 71 through line 73 and pass into washing tower and separator 75. Water vapor and hydrochloric acid may be washed from the entering gases by means of water fed into the upper portion of the tower through the line 71. The wash water is withdrawn from the bottom of the tower through the line 79 controlled by valve 81. By maintaining the separator 75 under superatmospheric pressure, the chlorine can be liquefied in the upper portion of the tower and separated from the remaining gas such as nitrogen, oxygen and hydrocarbons which escape from the top of the tower through the line 83 controlled by valve 85. Chlorine is withdrawn from the separator 75 through line 87 controlled by valve 89 and recycled through line 7 where it is mixed with the C₁ and C₂ hydrocarbons from the absorber. The mixture then passes to the reactor 91 in which chlorine is combined with the C₁ and C₂ hydrocarbons to form chlorides of these hydrocarbons. Make-up chlorine is added through line 92 controlled by valve 93. Reactor 91 may be maintained under atmospheric pressure or under superatmospheric pressure somewhat lower than that maintained in the separator 75 and may be cooled to control the reaction. The reaction products are withdrawn from the reactor 91 through line 94, compressed by means of compressor 95 and used to alkylate the heavy gasoline distillate in the reaction chamber 45.

Instead of chlorinating the C₁ and C₂ gases from absorber 3, these gases may be withdrawn from the system through line 96 controlled by valve 97 and methane and/or other paraffinic gas from an independent source fed through line 98 controlled by valve 99 to chlorinator 91. Moreover, methyl chloride from an extraneous source can be charged through line 100 controlled by valve 101 to the aluminum chloride reactor 45 and the necessity of chlorinating methane and/or ethane as part of the process, dispensed with.

It will be seen, therefore, that I have devised a unitary process for converting hydrocarbon oils and gases into a finished gasoline, the light fraction of which is high in unsaturates and the heavier fraction of which is high in saturated hydrocarbons and contains very little unsaturated hydrocarbon. The light fraction will consist predominantly of olefinic hydrocarbons with some aromatic hydrocarbons. The aromatic hydrocarbons in the light fraction are unobjectionable since they appear to be beneficial for low speed operation. In the heavy fraction of the gasoline will be present isoparaffins formed by the alkylation of the aliphatic unsaturated hydrocarbons and some aromatic hydrocarbons containing alkyl side chains. The presence of alkylated benzene and alicyclic hydrocarbons in the high boiling fraction is not objectionable since they appear to act like paraffinic hydrocarbons and therefore are beneficial for high speed performance.

Although I have shown and disclosed my invention in connection with a polyform process for producing unsaturated gasoline distillates and

a Friedel-Crafts type of process for saturating the heavy gasoline fraction, it will be understood that the invention is not limited to these specific steps. The invention in its broadest aspects covers the saturation of a higher boiling gasoline fraction rich in olefinic hydrocarbons and the blending thereof with a lower boiling highly unsaturated gasoline fraction, regardless of the manner in which the saturation is effected. For example, saturation may be effected by hydrogenation with hydrogen under pressures of the order of 800 pounds per square inch at temperatures of the order of 350°-400° F. in the presence of a catalyst, as, for example, one composed of copper, magnesium oxide and zinc oxide. The highly 15 unsaturated low boiling gasoline fraction may be prepared by either thermal or catalytic polymerization of hydrocarbon gases or by thermal reforming of naphtha at temperatures of the order of 1000-1050° F., or catalytic dehydrogenation of naphtha at temperatures of the order of 750-950° F. in the presence of a catalyst such as Activated Alumina impregnated with chromium oxide. The method and apparatus describe and show one way of accomplishing the objects of my invention.

The invention accomplishes the object of improving road performance of motor fuel without the necessity of increasing octane rating as measured by the A. S. T. M. method. Motor fuels produced in accordance with my invention will perform better than motor fuels of equal or even higher octane number prepared by well known methods.

It will be understood, however, that although the invention relies on modifying the nature of the compounds in the upper boiling fraction in order to obtain the desired motor fuel, not on the necessity of increasing the octane number of the fuel, in accordance with my invention the octane rating of the fuel as measured by the A. S. T. M. method is in fact increased without

suffering any decrease in yield of motor fuel. Alkylation or hydrogenation of the upper boiling fraction results in increased octane rating thereof and in an increased amount of liquid product within the motor fuel range.

5 I claim:

1. The method of preparing motor fuel which comprises charging a mixture of hydrocarbon oil and gas to a conversion zone, subjecting the mixture in said zone to conditions of time, temperature and pressure to convert a substantial portion thereof into unsaturated hydrocarbons boiling within the gasoline boiling range, separating from the reaction products a fraction boiling 10 within the upper gasoline boiling range, separating the reaction gases into a fraction containing predominantly C₃ and higher boiling hydrocarbons and a fraction containing predominantly C₁ and C₂ hydrocarbons, recycling the C₃ and higher boiling hydrocarbon fraction to the conversion zone, converting the C₁ and C₂ hydrocarbons to alkyl chlorides, alkylating the fraction boiling within the upper gasoline range by means of said alkyl chlorides in the presence of aluminum 15 chloride and blending with the alkylated fraction the hydrocarbons rich in unsaturates, boiling within the lower gasoline boiling range.

2. The method of preparing motor fuel which comprises converting hydrocarbon oil into hydrocarbons rich in olefines boiling within the gasoline boiling range and into hydrocarbon gases having from 1 to 4 carbon atoms per molecule, chlorinating C₁ and C₂ gases to alkyl chlorides, alkylating the higher boiling portion of the gasoline boiling range hydrocarbons by means of 20 said alkyl chlorides in the presence of aluminum chloride, and blending the resulting alkylate with the lower boiling gasoline boiling range olefinic hydrocarbons.
